(57) **CLAIM**

The ornamental design for a golf club shaft, as shown and described.

DESCRIPTION

FIG. 1 is a top right front elevational view of a golf club shaft showing my new design;

FIG. 2 is a right side elevational view, the left side elevational view being identified thereto;

FIG. 3 is a rear view, the front view being identified thereto;
FIG. 4 is a sectional view taken along line 4—4 of FIG. 3;
FIG. 5 is a right side view of another embodiment of my design, the left side being identical thereto; and,

FIG. 6 is a rear view of the other embodiment of my design the front view being identical thereto.

The broken line showing of is for illustrative purposes only and forms no part of the claimed design.
